UNITED STATES PATENT OFFICE

GUSTAVE N. MICHAUD, OF ST. PAUL, MINNESOTA

DESIGN FOR AN AUTOMOBILE SIGNAL BRACKET

Application filed April 4, 1930. Serial No. 35,158. Term of patent 8½ years.

To all whom it may concern:

Be it known that I, GUSTAVE N. MICHAUD, a citizen of the United States, residing at St. Paul, county of Ramsey, and State of Minnesota, have invented a new, original, and ornamental Design for Automobile Signal Bracket, of which the following is a specification, reference being had to the accompanying drawing, forming part thereof.

Figure 1 is a front view of an automobile signal bracket, showing my new design.

Figure 2 is a top view of the same.

I claim:

The ornamental design for an automobile signal bracket, as shown.

GUSTAVE N. MICHAUD.
